(57) **CLAIM**

The ornamental design for a sink, as shown and described.

DESCRIPTION

FIG. 1 is a top, front perspective view of a sink according to our new design;

FIG. 2 is a top plan view thereof;

FIG. 3 is a front elevational view thereof, the left side, right side and rear elevational views thereof being identical to the front shown; and,

FIG. 4 is a bottom plan view thereof.

The broken line representations in the figures are for the purpose of illustration only, and form no part of the claimed design.
